UNITED STATES PATENT OFFICE.

ROBERT L. G. DAY, OF SPOKANE, WASHINGTON, ASSIGNOR TO ROBERT W. DAY, OF LOS ANGELES, CALIFORNIA.

DESIGN FOR A CASING FOR A ROPE MACHINE.

Application filed June 22, 1921. Serial No. 479,663. Term of patent 14 years.

To all whom it may concern:

Be it known that I, ROBERT L. G. DAY, a citizen of the United States, residing at Spokane, in the county of Spokane and State of Washington, have invented a new, original, and ornamental Design for a Casing for a Rope Machine, of which the following is a specification, reference being had to the accompanying drawing, forming a part thereof.

Fig. 1 is a front view of a casing for a rope machine, showing my new design. Fig.

2 is an edge view of the same. Fig. 3 is a rear view of the casing for a rope machine.

I claim:

The ornamental design for a casing for a rope machine, as shown.

In testimony whereof, I have affixed my signature in presence of two witnesses.

ROBERT L. G. DAY.
